UNITED STATES PATENT OFFICE

GEORGE E. LEE, OF CLEVELAND, OHIO, ASSIGNOR, BY MESNE ASSIGNMENTS, TO MAHONING SAVINGS AND TRUST COMPANY, TRUSTEE, OF YOUNGSTOWN, OHIO, A CORPORATION OF OHIO

PRINTING PRESS

Application filed March 7, 1927. Serial No. 173,360.

My invention relates to printing presses, and the particular object of my invention is to provide a new and improved non-adjustable multi-color printing press. In the drawings accompanying this specification and forming a part of this application I have shown, for purposes of illustration, one form which my invention may assume, and in these drawings:

10 Figure 1 is a plan view of this embodiment of my invention,

Figure 2 is a front elevation thereof,

Figure 3 is a right end elevation thereof,

15 Figure 4 is a detail of the platen levelling mechanism taken on the line 4—4 of Figure 2,

Figure 5 is a fragmentary section taken on the line 5—5 of Figure 1,

20 Figure 6 is a fragmentary section taken on the line 6—6 of Figure 1,

Figure 7 is a fragmentary rear elevation,

Figure 8 is a section taken on the line 8—8 of Figure 1,

25 Figure 9 is a section taken on the line 9—9 of Figure 7,

Figure 10 is a section taken on the line 10—10 of Figure 3,

Figure 11 is an enlarged fragmentary front elevation,

20 Figure 12 is a section on the line 12—12 of Figure 11,

Figure 13 is a detail showing the ink disc revolving mechanism,

25 Figure 14 is a section on the line 14—14 of Figure 2,

Figure 15 is a section on the line 15—15 of Figure 11,

Figure 16 is an enlarged section on the line 16—16 of Figure 1,

30 Figure 17 is a front end elevation of one of the chases,

Figure 18 is a section on the line 18—18 of Figure 17, while

35 Figure 19 is a section on the line 19—19 of Figure 18.

The embodiment of my invention herein shown comprises a main frame 21 mounted upon a pedestal 22, substantially annular in shape, comprising sides 23 and 24, and supporting among other parts a fixed impres-

sion platen 25 and a movable bed platen 26.

The impression platen 25 is adjustably supported upon the upper faces of the sides 23 and 24 of the frame 21 by means of four sleeves 27 each screw-threadedly engaged within one of the cooperately screw-threaded apertures 28 formed at the four corners of the impression platen 25, and each rotatable in that aperture to vary the elevation of that corner of the impression platen 25 above the frame engaging lower face of that sleeve 27, and therefore the elevation of that corner of the impression platen 25 above the frame 21; and the impression platen 25 is held in adjusted position by means of bolts 29 passing through bores 30 in the sleeves 27, engaging in cooperately screw-threaded apertures 31 in the upper faces of the sides 23 and 24, and serving to hold the sleeves 27 and impression platen 25 firmly clamped to the frame 21, and also to hold the sleeves 27 against rotation; and therefore the impression platen 25 against variation in elevation or angle.

75 The bed platen 26 is supported by means of a pair of rearwardly extending arms 32 pivotally mounted upon a cross shaft 33 carried in arms 34 integral with the sides 23 and 24 of the frame 21 and projecting rearwardly from the upper portion thereof; and is actuated by means of a cross shaft 179 supported in the sides 144 of the bed platen 26 and forming the pivot for two eccentric straps 180 actuated by eccentrics 181 carried by the main press-operating shaft 68.

80 Mounted at the right hand side of the press is web delivering means herein shown as a pair of brackets 35 carried by the pedestal 22 and provided with bearings 36 adapted to support a shaft 37 carrying a roll 38, brackets 39 carried at the lower edge of the frame 21 and rotatably supporting the web guiding roller 40, and brackets 41 carried at the upper end of the side 24 provided with trunnions 42 and 43 carrying respectively a first roll 44 over which the web passes and a second roll 45 having its lower face slightly above the plane 100

in which the web passes through the press, and under which the web passes just before it enters the press. In order to guide the web laterally the roll 44 is provided with sides 46 and 47, in order to provide for web of somewhat different width the side 47 is formed separate from the roll 44 and secured thereto in the desired adjusted position by means of a suitable set screw 48, in order to aline the web with the printing mechanism the entire roll 44 may be adjusted along its own axis by corresponding advance and retracting of its two trunnions 42, in order to facilitate guiding of the web the sides 46 and 47 are provided with bevelled inner faces and the roll 38 is permitted to over-run so that upon the termination of each advance of the web the web will bulge outwardly above the roller 44 to be drawn back by the next advance of the web accurately alined by engagement with the sides 46 and 47. The roller 44, because of its position, also serves to impose upon the web a reverse bend effective to remove substantially the entire coil from the web, and to deliver the web to the press substantially flat.

Disposed at the left hand side of the press is an auxiliary frame 49 carrying the web feeding and web severing mechanism.

The web feeding mechanism herein shown includes: web lower face engaging means comprising two shafts 50 spaced from each other in the direction of extent of the web, 35 suitably supported in the side plates 52 of the auxiliary frame 49, each carrying between the side plates 52 a pair of discs 53 rotatable with that shaft 50 and positioned to engage the opposite edges of the web, and 40 each carrying exteriorly of the rear side plate 52 a gear 54; actuating means for the web lower face engaging means comprising a gear 55 mounted on a stud 56 between the two gears 54 meshing with both the gears 54 45 and carrying a ratchet wheel 57 secured thereto by means of suitable pins 58 and engaged by a dog 59 pivoted at 60 to a segment 61 rotatable on the stud 56 and engaged by a rack 62 slidably 50 mounted in the auxiliary frame 49 and pivoted at its lower end to a lever 63 pivoted to the main frame 21 at 64 and actuated by an eccentric strap 65 pivoted to the lever 63 at 66 and operated by means of an eccentric 67 mounted on the main press-operating shaft 68; web upper face engaging means comprising a pair of shafts 70 each rotatably mounted in slots 71 formed in the upper edge of the side plates 52, each carrying 60 loosely a pair of discs 72 opposing the corresponding discs 53 and cooperating therewith to grip the web therebetween, and biased upwardly, to remove the discs 72 from the web, by springs 73 disposed in recesses 69 formed in the side plates 52 and

acting upwardly against the ends of the shafts 70; and web gripping means consisting of a bar 74 provided at its ends with semi-circular recesses 75 engaging loosely in recesses 76 disposed centrally of the two shafts 70, a stud 77 secured to the center of the bar 74 by screw-threaded engagement providing for adjustment, and a spring 78 compressed between the upper end of the stud 77 and a plate 79 pivoted on a shaft 82 fixed in upwardly extending projections 80 on the side plates 52 and normally held in depressed position, with the spring 78 compressed and the web gripped, by a cam 81 rotatably mounted upon the shaft 82 and 75 rotatable by means of a handle 83 to retract the upper abutment 79 of the spring 78 and thus remove the action of the spring 78 theretofore forcing the upper discs 72 against the lower discs 53 to thus permit the 80 weaker springs 73 to raise the upper discs 72 clear of the web, all, however, without in any way interfering with the adjustment of the tension by which the web is to be engaged, regulated by the adjustment between the stud 77 and the bar 74.

The web severing means herein shown comprises a fixed knife 84 secured to the ends of the side plates 52, and a movable knife 85 pivotally mounted upon a stud 86 carried by a lug 87 projecting from the rear side plate 52. The movable knife 85 is biased against the fixed knife 84 by means of a spring 202 compressed beneath the head of the stud 86, is provided with a bell-crank 100 arm 88, and is normally held retracted by the action on the bell-crank arm 88 of a link 89 pivoted to the bell-crank arm 88 at 90, restrained at the other end by a fork 91 embracing the main press-operating shaft 105 68, and controlled, through a roller 92 carried adjacent the fork 91, by a cam 93 mounted on the main press-operating shaft 68 and provided with a rim 51 engaging the roller 92, elevated over its entire periphery 110 except for a single depression 94, and therefore effective to hold the roller 92 elevated, and the movable knife 85 retracted, except when the depression 94 registers with the roller 92, and at that time the movable knife 115 85 is swiftly and sharply advanced by means of a tension spring 95 connected between an aperture 96 in the end of the bell-crank arm 88 and a stud 97 projecting outwardly from the side 23 of the main frame 21.

The two side plates 52 are secured together by the fixed knife 84, and by such additional cross members as may be required, not shown, and the entire auxiliary frame 49 is supported from the main frame 21 by means of a pair of square bars 98 projecting outwardly from the side 23 of the main frame side 21 and engaging slidably within apertures 99 formed at the lower edge 125 of the auxiliary frame side plates 52 to per-

mit adjustment of the auxiliary frame 49 relative to the main frame 21 in the direction of the length of the web, to thus permit positioning of the auxiliary frame 49 at that point where the severing mechanism registers with the printing mechanism accurately and correctly; and the auxiliary frame 49 may be locked in this adjusted position by means of set screws 100 passing through the slides 99 into engagement with the bars 98.

Mounted on the bed platen 26 are a plurality of chases 101, and mounted on the upper platen 25 are a plurality of cooperating impression plates 102.

Each of the impression plates 102 is registered laterally by means of a keyway 103 cooperating with a key 104 relatively permanently positioned within a keyway 105 formed in the face plate 190 of the fixed platen 25, and each of the impression plates 102 is registered longitudinally of the key 104, and held assembled on the fixed platen 25, by means of a pin 106 having a reduced tip 107 projecting through an aperture 108 in the face plate 190 of the fixed platen 25, held normally retracted by means of a spring 109 compressed between the upper face of the face plate 190 of the fixed platen 25 and the shoulder 199 formed by the reduced extension 107, but projectable by means of a handle 110 into position with the screw threaded end portion 191 of its reduced extension 107 engaging within a correspondingly screw threaded aperture 111 in the impression plate 102, the projection of the extension 107 being facilitated, particularly when the plate 102 is not exactly alined, by a bevelled tip 192 carried by the extension 107 beyond the end-portion 191.

Each of the chases 101 comprises a solid base 112 provided with integral fixed sides 113 and 114, a rear end 115 normally retained in assembled position by means of screws 116 passing into the ends of the sides 113 and 114, and a front end 117 secured against direct movement away from the sides 113 and 114 by means of similar screws 118 and 119, but provided with a slot 120 below the aperture for the screw 119 to permit pivotal movement of the front end 117 about the screw 118 into position permitting any part or all of the form being slipped from the chase through the open front end thereof. The side 114 is provided with the usual screw sleeves 120 adapted to act against a plate 121 to clamp the form laterally, the front end 117 is provided with similar screw sleeves 122 adapted to act against a plate 123 to clamp the form longitudinally, and the front end 117 may be held in closed position by the action of the screw sleeves 122 in effect clamping the front end 117 between the plate 123 and the heads of

the screws 118 and 119, or, if desired, the screws 118 and 119 may be tightened to directly hold the front end 117 firmly clamped in closed position.

Each chase bottom plate 112 is registered with the face plate 200 of the bed platen 26 in a manner similar to that by which each impression plate 102 is registered with the face plate 190 of the impression platen 25, and accordingly each chase bottom plate 112 is provided with a keyway 124 adapted to receive a key 125 normally held within a keyway 126 formed in the face plate 200 of the bed platen 26, and with a screw-threaded recess 127 adapted to receive the screw-threaded end 193 of a pin 128 passing through an aperture 129 in the face plate 200 of the bed platen 26, normally held retracted by its own weight, held against complete disassociation from the face plate 200 by means of a fork 130 secured to the under side of the face plate 200 by draft screws 131, projectable into chase holding position by means of a suitable finger piece 132, and provided with a bevelled tip 194 facilitating insertion.

It will be appreciated by those skilled in the art that by means of this construction any impression member, either an impression plate or a chase, may be removed and replaced without disturbing the register thereof with the web or with the other impression members or with the severing mechanism, and also that because of this construction two impression plates, or two chases, 100 may be interchanged, as, for example, to reverse the colors in which certain portions of the matter are printed without the necessity for changing or cleaning the inking mechanism; and from the above description it will 105 be apparent to those skilled in the art that each chase and each impression plate is registered accurately and in such manner that it can be removed and replaced, or interchanged with another chase or plate, without in any manner disturbing this register. This is particularly important in the press shown herein, since in this press the registering means for the chases, and of course also the registering means for the impression plates, are separated by spacing exactly 110 twice the distance subtended by the active face of a chase, the severing mechanism is separated from the last chase by a spacing exactly equal to an even multiple of 115 this distance, and the feeding mechanism advances the web at each operation exactly this distance, whereby the chases are all accurately registered with the web as the web advances from one chase to the next, and the severing mechanism is also accurately registered with the web as the web advances from the last chase.

Ink is supplied to the chases by means of three inking rollers 133 provided at their 120 125 130

ends with spindles 134 carrying bushings 135 received within recesses 136 in the side plates 137 of a roller frame 138 comprising also tie-rods 139 and mounted for reciprocation on the bed platen 26 by means of lips 140 projecting from the lower ends of the side plates 137 to define longitudinal recesses 141 which receive rails 142 projecting from tracks 143 carried by the upper face 10 of the edges 144 of the bed platen 26. The roller frame 138 is reciprocated from the retracted position herein shown forwardly over inking discs 145 and the chases 101 by means of links 146 pivoted at one end to 15 the roller frame 138 and at the other end to the free ends of arms 147 secured to a cross-shaft 148 mounted in the sides 23 and 24 of the main frame 21 and itself actuated through one of the arms 147 by an eccentric 20 strap 149 pivoted to this arm 147 at 150 and actuated by an eccentric 151 mounted upon the main press-operating shaft 68. The rollers 133 are supported in this movement directly by type-high bearers 152 carried 25 by the bed platen 26, and also by discs 153 of equal diameter with the rollers 133 fixed on the spindles 134 of the rollers 133 and riding on the type-high upper faces 201 of the track 143, and the rollers 133 are pressed 30 downwardly into engagement with the bearers 152, and to engage the discs 153 with the upper faces 201 of the tracks 143, by means of a plurality of springs 155 mounted on a pair of plates 156 disposed one at each side 35 of the roller frame 138 and held in position by screws 157 extending through bayonet slots 158 to permit removal of the plates 156, and consequent release of the rollers 133 from the action of the springs 155, and subsequent 40 removal of the rollers 133, all by movement of the plates 156 longitudinally of the roller frame side plates 137 normally prevented by the presence within apertures 159 in the plates 136 of pins 160 carried by 45 springs 161 supported in the roller frame side plates 137 and deformable to retract the pins 160 from the apertures 159 to permit such longitudinal movement, and such removal of the plate 156 and springs 155.

50 The bearers 152 are supported on the face plate 200 of the bed platen 26 by means of studs 162 reciprocable in apertures 163 in bearer bases 203 secured to the face plate 200, are resiliently held at type level by means of springs 164 projecting from recesses 195 in the bases 203 and compressed between the lower surface of the bearers 152 and the bearer bases 203, and during printing, and to prevent contact thereof with the 60 web, are depressed by means of plates 165 secured to the impression platen 25 and projecting beneath the type level to contact the bearers 152 before the bearers reach type level, and to hold the bearers 152 below type level; while contact of the web with the

upper faces 201 of the tracks 143 is prevented by means of plates 166 and 167 secured to the inner faces of the tracks 143 projecting just above the level of the upper faces 201 of the tracks 143 to raise the web 70 slightly above the upper faces 201 when the upper faces 201 would otherwise contact the web during printing, the plate 167 being formed with a web engaging surface designed to prevent smearing of the ink on 75 the web and herein shown as consisting of a multiplicity of fine pin points 196.

The press herein shown also comprises means for holding the web tightly against the impression plates 102 during printing, 80 and for maintaining the web so held until after the bed platen has receded, to thus strip the web from the forms, this means being provided herein between the active surfaces of the impression plates 102 and comprising between each pair of active surfaces a holding means consisting of a bar 168 having its ends extended to form sides 169 extending to pins 170 projecting from the corresponding bearer depressing plates 165, 90 having these ends then coiled above these pins 170 to form helical springs 197, and having these ends then projecting further as extensions 171 disposed well below the sides 169 and in position to be engaged by the corresponding bearer 152 to force the bar 168 upwardly into position clamping the web against the impression plates 102 at a time at least not later than the time when the bearer 152 contacts the plates 165, and to hold the bars 168 firmly in this web-clamping position during printing, and for a sufficient time thereafter to insure that the forms strip from the web. In the press herein shown the web is actually firmly 100 clamped even before the bearers 152 have engaged the bearer depressing plates 165, and remains clamped until well after the bearers 152 have separated from the bearer depressing plates 165, this function resulting from the fact that the extensions 171 are disposed so far beneath the sides 169 that the rods 168 force the web against the impression plates 102 well before the bearers 152 reach the bearer depressing plates 165, 115 after which the further movement of the bearers 152 is permitted by resilient deformation of the helical spring sections 197 about the supporting pins 170.

The printing press herein shown also includes means for rotating the inking discs 145, this means comprising a cross bar 172 mounted in the sides 144 of the bed platen 26, operated by means of an arm 173 carrying a pin 174 engaged by the roller frame 138 as the roller frame 138 advances, and carrying a plurality of arms 175 carrying on their free ends dogs 176 held by gravity with their pawls 177 in engagement with ratchet 120 125 130

teeth 178 formed on the lower faces of the inking discs 145.

The main press-operating shaft 68 is herein operated from an electric motor 182 by means of a belt 184 passing over pulleys 185 and 186 mounted respectively on the shaft 187 of the motor 182 and on a cross shaft 183 connected to the main press-operating shaft 68 by means of a worm 188 carried on the cross shaft 183 and engaging a worm gear 189 mounted on the main press-operating shaft 68; and the various mechanisms operated by the main press-operating shaft are of course properly synchronized, in the embodiment of my invention herein shown the severing mechanism operates practically synchronously with the printing, the inking rollers 133 advance as the bed platen 26 recedes and recede as the bed platen 26 advances, and the web feeding mechanism actuating rack 62 rises through its idle stroke while the bed platen 26 is completing its approach to the impression platen 25 and beginning its retraction from the impression platen 25, and descends through its web feeding stroke while the bed platen 26 is completing its retraction from the impression platen 25 and beginning its subsequent advance toward the bed platen 25.

For convenience I may mount on the end of the bars 98 a tray 198 to receive the web sections as they are cut off by the severing mechanism.

From the above description it will be obvious to those skilled in the art that I have provided a new and improved non-adjustable multi-color printing press, and accordingly that I have accomplished at least the principal object of my invention. More particularly, it will be obvious to those skilled in the art that the embodiment of my invention herein shown and described provides new and improved mechanism for flattening and alining and supporting and deflecting and feeding the web; for registering the chases with the bed platen and with each other, and the impression plates with the impression platen and with each other, and the chases and impression plates with the web severing mechanism; for supporting the inking rollers; for adjusting and levelling the fixed platen; for holding and supporting the form; and for registering the severing mechanism with the chases.

At the same time it also will be obvious to those skilled in the art that the embodiment of my invention herein shown and described embodies advantages other than those particularly pointed out or suggested herein, and also that the embodiment of my invention herein shown and described may be variously changed and modified without departing from the spirit of my invention or sacrificing the advantages thereof.

And particularly it will be understood that one or more of the impression units may be used for embossing rather than for printing.

It therefore will be understood by those skilled in the art that the disclosure herein is clearly illustrative only, and that my invention is not limited thereto.

I claim:—

1. In a printing press: impression mechanism for impressing a web; and means for feeding said web through said impression mechanism comprising a roller positioned just ahead of said impression mechanism and provided with sides for alining said web laterally, one of said sides being adjustable on said roller to provide for variations in web width, and said roller being axially adjustable as a unit to aline said web accurately with said impression mechanism. 85

2. In a printing press: impression mechanism for impressing a web; a web supply free to over-run; and means for feeding said web through said impression mechanism intermittently comprising a roller positioned just ahead of said impression mechanism and provided with bevelled sides for alining said web laterally as the slack therein is taken up by operation of said feeding means, one of said sides being adjustable on said roller 95 to provide for variations in web width, and said roller being axially adjustable as a unit to aline said web accurately with said impression mechanism.

3. In a printing press: a bed; a plurality 100 of impressing means carried by said bed alined along said bed; impression platen means mounted to cooperate with said impression means; means for feeding a web longitudinally of said bed; means for effecting relative approachment of said impressing means and said platen means to impress said web, and relative separation of said impressing means and said platen means to free said web; and supporting means for 110 said web actuated upon said approachment and acting upon said web intermediate the active surfaces of said impressing means and to move said web into firm engagement with said platen means before said impressing means begins to impress said web. 115

4. In a printing press: a bed; a plurality 120 of impressing means carried by said bed alined along said bed; impression platen means mounted to cooperate with said impression means; means for feeding a web longitudinally of said bed; means for effecting relative approachment of said impressing means and said platen means to impress said web, and relative separation of said impressing means and said platen means to free said web; and supporting means for 125 said web actuated upon said approachment and acting upon said web intermediate the active surfaces of said impressing means and 130

to move said web into firm engagement with said platen means before said impressing begins to impress said web, and to retain said web in such engagement until after 5 said impressing means have stripped from said web.

5. In a printing press: a bed; a plurality of impressing means carried by said bed aligned along said bed; impression platen 10 means mounted to cooperate with said impression means; an inking roller mounted to be moved over said impressing means; a type-high depressible bearer for said inking roller; means for feeding a web longitudinally of said bed; means for effecting relative approachment of said impressing means and said platen means to impress said web, and relative separation of said impressing means and said platen means to 15 free said web; and supporting means for said web actuated by said bearer upon said approachment and acting upon said web intermediate the active surfaces of said impressing means and to move said web into 20 firm engagement with said platen means before said impressing means begins to impress said web.

6. In a printing press: impression mechanism for impressing a web; and means 30 for feeding said web through said impression mechanism comprising two rollers engaging one face of said web at points spaced along said web, rotary means engaging the other face of said web opposite said rollers, 35 driven gears carried by said rollers, a single driving gear engaging both said driven gears, and means for operating said driving gear.

7. In a printing press: impression mechanism for impressing a web; and means for feeding said web through said impression mechanism comprising first rotary means engaging one face of said web, cooperating rotary means engaging the other face of 45 said web opposite said first rotary means, biasing means tending to effect approachment of said rotary means to grip said web and adjustable to vary the pressure with which said rotary means engage said web, 50 and means for relieving the action of said biasing means to permit separation of said rotary means to free said web operable without affecting the adjustment of said biasing means.

55. 8. In a printing press: impression mechanism for impressing a web; and means for feeding said web through said impression mechanism comprising first rotary means engaging one face of said web, cooperating 60 rotary means engaging the other face of said web opposite said first rotary means, biasing means tending to effect approachment of said rotary means to grip said web and adjustable to vary the pressure with 65 which said rotary means engage said web,

means for relieving the action of said biasing means to permit separation of said rotary means to free said web operable without affecting the adjustment of said biasing means, and means to separate said rotary means when such separation is so permitted. 70

9. In a printing press: impression mechanism for impressing a web; and means for feeding said web through said impression mechanism comprising at least two pair of discs each pair arranged to engage opposite edges of one face of said web, a single biasing means for urging said discs against said web, and equalizing means interposed between said biasing means and said discs to cause said biasing means to exert equal pressure on each of said discs. 75

10. In a printing press: impression mechanism for impressing a web; and means for feeding said web through said impression mechanism comprising at least two pair of discs each pair mounted on a single axle and arranged to engage opposite edges of one face of said web, a single biasing means for urging said discs against said web, and a bar engaged centrally and loosely by said biasing means and engaging said axles at its ends and loosely and centrally, to cause said biasing means to exert equal pressure on each of said discs. 80

11. In a printing press: a bed; printing means carried by said bed; an inking roller carried by said bed and disposed at type level; means for advancing said inking roller over said printing means; a bearer for said roller carried by said bed at type level; impression platen means mounted to cooperate with said printing means; means for supporting a web along said platen means; means for effecting relative approachment of said printing means and said platen means to imprint said web, and relative separation of said printing means and said platen means to free said web; and means acting during said approachment to depress said web opposite said bearer to prevent said bearer contacting said web. 90

12. In a printing press: a bed; printing means carried by said bed; an inking roller carried by said bed, and disposed at type level; means for advancing said inking roller over said printing means; a bearer for said roller carried by said bed at type level; impression platen means mounted to cooperate with said printing means; means for supporting a web along said platen means; means for effecting relative approachment of said printing means and said platen means to imprint said web, and relative separation of said printing means and said platen means to free said web; and means carried by said bed acting during said approachment to depress said web opposite said bearer to prevent said bearer contacting said web. 100

13. In a printing press: a bed; printing means carried by said bed; an inking roller carried by said bed, and disposed at type level; means for advancing said inking roller over said printing means; a bearer for said roller carried by said bed at type level; impression platen means mounted to cooperate with said printing means; means for supporting a web along said platen means; means for effecting relative approachment of said printing means and said platen means to imprint said web, and relative separation of said printing means and said platen means to free said web; and means carried by said bearer and projecting just above said bearer acting during said approachment to depress said web opposite said bearer to prevent said bearer contacting said web.

14. In a printing press: a bed; printing means carried by said bed; an inking roller carried by said bed, and disposed at type level; means for advancing said inking roller over said printing means; a bearer for said roller carried by said bed at type level; impression platen means mounted to cooperate with said printing means; means for supporting a web along said platen means; means for effecting relative approachment of said printing means and said platen means to imprint said web, and relative separation of said printing means and said platen means to free said web; and means engaging said web formed not to smear printing on said web acting during said approachment to depress said web opposite said bearer to prevent said bearer contacting said web.

15. In a printing press: a base provided with an aperture; an impression member, provided with an aperture positioned to aline with said aperture in said base when said member is accurately positioned on said base; and means for accurately positioning said member on said base comprising a key and a keyway formed one on said member and the other on said base, and a pin adapted to be inserted through said apertures.

16. In a printing press: a base provided with an aperture; an impression member, provided with an aperture positioned to aline with said aperture in said base when said member is accurately positioned on said base; and means for accurately positioning said member on said base comprising a key and a keyway formed one on said member and the other on said base, and a pin carried within one of said apertures adapted to be inserted through the other of said apertures.

17. In a printing press: a base provided with an aperture; an impression member, provided with an aperture positioned to aline with said aperture in said base when said member is accurately positioned on said base; and means for accurately positioning said member on said base comprising a key

and a keyway formed one on said member and the other on said base, and a pin carried in one of said apertures normally retracted, adapted to be inserted through the other of said apertures, and formed to be secured in inserted position.

18. In a printing press: a base provided with an aperture; an impression member, provided with an aperture positioned to aline with said aperture in said base when said member is accurately positioned on said base; and means for accurately positioning said member on said base comprising a key and a keyway formed one on said member and the other on said base, and a pin adapted to be inserted through said apertures provided with a bevelled end to facilitate such insertion.

19. In a printing press: a bed formed to receive a series of chases carried by said bed in a corresponding series of chase positions extending along said bed; a plurality of chases each adapted to be received on said bed in any one of said chase positions; means for feeding a web longitudinally of said bed for each section thereof to be imprinted at each of said chase positions successively; a series of registering means carried by said bed one for each of said chase positions and each functionally identical with each other; and a plurality of registering means carried one by each of said chases and each functionally identical with each other and adapted to cooperate functionally identically with each of said registering means carried by said bed; each of said chases being removable without affecting the relation thereto of its said registering means or the relation to said bed of the said registering means carried by said bed; whereby said chases may be interchanged on said bed without disturbing the register thereof on said web.

20. In a printing press: impression mechanism for impressing at each operation over a limited flat section of a long web; means for supporting rolled web for unrolling; and means for feeding said web through said impression mechanism, and for removing the coil from said web, comprising a roller positioned just ahead of said impression mechanism having said web passing thereover reversely curved to remove substantially the entire coil from said web, and to present said web to said impression mechanism substantially flat, and provided with sides for alining said web laterally, one of said sides being adjustable on said roller to provide for variations in web width, and said roller being axially adjustable as a unit to aline said web accurately with said impression mechanism.

21. In a printing press: impression mechanism for impressing a web; and means for feeding said web through said impression

mechanism comprising two rollers engaging one face of said web at points spaced along said web, rotary means engaging the other face of said web opposite said rollers, driven 3 gears carried by said rollers, a single driving gear engaging both said driven gears, and operating means for advancing said web intermittently connected to said driving gear and constructed to accelerate said web 10 gradually from rest to maximum feeding speed.

22. In a printing press: impression mechanism for impressing a web; and means for feeding said web through said impression mechanism 15 comprising two pairs of discs each pair arranged to engage opposite edges of said web, rotary means engaging the other face of said web opposite said discs, biasing means tending to urge said discs against said 20 web and adjustable to vary the pressure with which said discs engage said web, equalizing means interposed between said biasing means and said discs to cause said disc to engage said web equally, and means for relieving the action of said biasing means to 25 permit retraction of said disc to free said web operable without affecting the adjustment of said biasing means.

23. In a printing press: impression mechanism for impressing a web; and means for feeding said web through said impression mechanism comprising a roller positioned ahead of said impression mechanism and provided with sides for alining said web laterally, said sides being each adjustable laterally of said web to adjust for variations in web width and to aline said web accurately with said impression mechanism.

24. In a printing press: impression mechanism for impressing a web; and means for feeding said web through said impression mechanism comprising a roller positioned ahead of said impression mechanism and provided with bevelled sides for alining said 45 web laterally, said sides being each adjustable laterally of said web to adjust for variations in web width and to aline said web accurately with said impression mechanism.

25. In a printing press: impression mechanism for impressing a web; a web supply free to over-run; and means for feeding said web through said impression mechanism intermittently comprising a roller positioned ahead of said impression mechanism and 55 provided with bevelled sides for alining said web laterally as the slack therein is taken up by operation of said feeding means, said sides being each adjustable laterally of said web to adjust for variations in web width 60 and to aline said web accurately with said impression mechanism.

26. In a printing press: impression mechanism for impressing a web; and means for feeding said web through said impression mechanism comprising a roller positioned

ahead of said impression mechanism and provided with sides for alining said web laterally, one of said sides being adjustable on said roller to provide for variations in web width, and said roller being axially adjustable as a unit to aline said web accurately with said impression mechanism. 70

27. In a printing press: impression mechanism for impressing a web; and means for feeding said web through said impression mechanism comprising a roller positioned ahead of said impression mechanism and provided with bevelled sides for alining said web laterally, one of said sides being adjustable on said roller to provide for variations in web width, and said roller being axially adjustable as a unit to aline said web accurately with said impression mechanism. 75

28. In a printing press: impression mechanism for impressing a web; a web supply free to over-run; and means for feeding said web through said impression mechanism intermittently comprising a roller positioned ahead of said impression mechanism and provided with bevelled sides for alining said web laterally as the slack therein is taken up by operation of said feeding means, one of said sides being adjustable on said roller to provide for variations in web width, and said roller being axially adjustable as a unit to aline said web accurately with said impression mechanism. 80

90

95

29. In a printing press: a bed; a plurality

100 of impressing means carried by said bed alined along said bed; impression platen means mounted to cooperate with said impression means; means for feeding a web longitudinally of said bed; means for effecting relative approachment of said impressing means and said platen means to impress said web, and relative separation of said impressing means and said platen means to free said web; and supporting means for said web actuated upon said approachment 110 and comprising engaging means acting upon said web intermediate the active surfaces of said impressing means and resilient actuating means operating said engaging means yieldably to move said web into firm engagement with said platen means before said impressing means begins to impress 115 said web.

proachment and acting upon said web intermediate the active surfaces of said impressing means and to move said web into firm engagement with said platen means before said impressing means begins to impress said web.

31. In a printing press: a bed; a plurality of impressing means carried by said bed alined along said bed; impression platen means mounted to cooperate with said impression means; an inking roller mounted to be moved over said impressing means; a bearer for said inking roller; means for feeding a web longitudinally of said bed; means for effecting relative approachment of said impressing means and said platen means to impress said web, and relative separation of said impressing means and said platen means to free said web; and supporting means for said web actuated by said bearer upon said approachment and acting upon said web intermediate the active surfaces of said impressing means and to move said web into firm engagement with said platen means before said impressing means begins to impress said web.

32. In a printing press: a bed; a plurality of impressing means carried by said bed alined along said bed; impression platen means mounted to cooperate with said impression means; means for feeding a web longitudinally of said bed; means for effecting relative approachment of said impressing means and said platen means to impress said web, and relative separation of said impressing means and said platen means to free said web; and supporting means for said web actuated by said bed upon said approachment and comprising engaging means acting upon said web intermediate the active surfaces of said impressing means and resilient actuating means operating said engaging means yieldably to move said web into firm engagement with said platen means before said impressing means begins to impress said web.

33. In a printing press: a bed; a plurality of impressing means carried by said bed alined along said bed; impression platen means mounted to cooperate with said impression means; an inking roller mounted to be moved over said impressing means; a bearer for said inking roller; means for feeding a web longitudinally of said bed; means for effecting relative approachment of said impressing means and said platen means to impress said web, and relative separation of said impressing means and said platen means to free said web; and supporting means for said web actuated by said bearer upon said approachment and comprising engaging means acting upon said web intermediate the active surfaces of said impressing means and resilient actuating means operating said engaging means yieldably to move said web

into firm engagement with said platen means before said impressing means begins to impress said web.

34. In a printing press: a bed; a plurality of impressing means carried by said bed alined along said bed; impression platen means mounted to cooperate with said impression means; an inking roller mounted to be moved over said impressing means; a type-high depressible bearer for said inking roller; means for feeding a web longitudinally of said bed; means for effecting relative approachment of said impressing means and said platen means to impress said web, and relative separation of said impressing means and said platen means to free said web; and supporting means for said web actuated by said bearer upon said approachment and comprising engaging means acting upon said web intermediate the active surfaces of said impressing means and resilient actuating means operating said engaging means yieldably to move said web into firm engagement with said platen means before said impressing means begins to impress said web.

35. In a printing press: impression mechanism for impressing a web; and means for feeding said web through said impression mechanism comprising two rollers engaging one face of said web at points spaced along said web, rotary means engaging the other face of said web opposite said rollers, rotary driven members carried by said rollers, a single driving member actuating both said rotary driving members, and means for operating said single driving member.

36. In a printing press: impression mechanism for impressing a web; and means for feeding said web through said impression mechanism comprising two rollers engaging one face of said web at points spaced along said web, rotary means engaging the other face of said web opposite said rollers, rotary driven members carried by said rollers, a single driving member engaging both said driven members, and means for operating said driving member.

37. In a printing press: impression mechanism for impressing a web; and means for feeding said web through said impression mechanism comprising two rollers engaging one face of said web at points spaced along said web, rotary means engaging the other face of said web opposite said rollers, rotary driven members carried by said rollers, a single rotary driving member actuating both said driven members, and means for operating said driving member.

38. In a printing press: impression mechanism for impressing a web; and means for feeding said web through said impression mechanism comprising two rollers engaging one face of said web at points spaced along said web, rotary means engaging the other

face of said web opposite said rollers, driven gears carried by said rollers, a single driving gear actuating both said driven gears, and means for operating said driving gear.

- 5 39. In a printing press: impression mechanism for impressing a web; and means for feeding said web through said impression mechanism comprising two rollers engaging one face of said web at points spaced along 70
10 said web, rotary means engaging the other face of said web opposite said rollers, rotary driven members carried by said rollers, a single rotary driving member engaging both said driven members, and means for operating 75
15 said driving member.

40. In a printing press: impression mechanism for impressing a web; and means for feeding said web through said impression mechanism comprising two rollers engaging 80
20 the margins of one face of said web at points spaced along said web, rotary means engaging the other face of said web opposite said rollers, rotary driven members carried by said rollers, a single driving member actuating 85
25 both said rotary driving members, and means for operating said single driving member.

41. In a printing press: impression mechanism for impressing a web; and means for 90
30 feeding said web through said impression mechanism comprising first rotary means engaging one face of said web, cooperating rotary means engaging the other face of said web opposite said first rotary means, biasing 95
35 means tending to effect approachment of said rotary means to grip said web and adjustable to vary the pressure with which said rotary means engage said web, and an abutment for said biasing means returnably 100
40 movable from active position for relieving the action of said biasing means to permit separation of said rotary means to free said web operable without affecting the adjustment of said biasing means.

- 45 42. In a printing press: a bed; printing means carried by said bed; an inking roller carried by said bed, and disposed at type level; means for advancing said inking roller over said printing means; a bearer for said 105
50 roller carried by said bed at type level; impression platen means mounted to cooperate with said printing means; means for supporting a web along said platen means; means for effecting relative approachment 110
55 of said printing means and said platen means to imprint said web, and relative separation of said printing means and said platen means to free said web; and means having pin points engaging said web and 115
60 acting during said approachment to depress said web opposite said bearer to prevent said bearer contacting said web.

43. In a printing press: a bed; printing means carried by said bed; an inking roller carried by said bed, and disposed at type 120
65

level; means for advancing said inking roller over said printing means; a bearer for said roller carried by said bed at type level; impression platen means mounted to cooperate with said printing means; means for supporting a web along said platen means; means for effecting relative approachment of said printing means and said platen means to imprint said web, and relative separation of said printing means and said platen means to free said web; and means carried by said bed engaging said web, formed not to smear printing on said web, and acting during said approachment to depress said web opposite said bearer to prevent said 80
125 bearer contacting said web.

44. In a printing press: a bed; printing means carried by said bed; an inking roller carried by said bed, and disposed at type level; means for advancing said inking roller over said printing means; a bearer for said roller carried by said bed at type level; impression platen means mounted to cooperate with said printing means; means for supporting a web along said platen means; means for effecting relative approachment of said printing means and said platen means to imprint said web, and relative separation of said printing means and said platen means to free said web; and means carried by said bearer and projecting just above said bearer engaging said web, formed not to smear printing on said web, and acting during said approachment to depress said web opposite said bearer to prevent said 100
130 bearer contacting said web.

45. In a printing press: a bed; printing means carried by said bed; an inking roller carried by said bed, and disposed at type level; means for advancing said inking roller over said printing means; a bearer for said roller carried by said bed at type level; impression platen means mounted to cooperate with said printing means; means for supporting a web along said platen means; means for effecting relative approachment of said printing means and said platen means to imprint said web, and relative separation of said printing means and said platen means to free said web; and means carried by said bed having pin points engaging said web and acting during said approachment to depress said web opposite said bearer to prevent said bearer contacting said web.

46. In a printing press: a bed; printing means carried by said bed; an inking roller carried by said bed, and disposed at type level; means for advancing said inking roller over said printing means; a bearer for said roller carried by said bed at type level; impression platen means mounted to cooperate with said printing means; means for supporting a web along said platen means; means for effecting relative approachment of said printing means and said platen means 120
125

to imprint said web, and relative separation of said printing means and said platen means to free said web; and means carried by said bearer and projecting just above said bearer having pin points engaging said web and acting during said approachment to depress said web opposite said bearer to prevent said bearer contacting said web.

47. In a printing press: a base provided with an aperture; an impression member provided with an aperture positioned to aline with said aperture in said base when said member is accurately positioned on said base, one of said apertures being screw-threaded; and means for accurately positioning said member on said base comprising a key and a keyway formed one on said member and the other on said base, and a screw-threaded pin carried in the other of said apertures normally retracted, adapted to be inserted through said one aperture, and to be screw-threadedly secured in inserted position.

48. In a printing press: a base provided with an aperture; an impression member provided with an aperture positioned to aline with said aperture in said base when said member is accurately positioned on said base; and means for accurately positioning said member on said base comprising a key and a keyway formed one on said member and the other on said base, and a pin carried within one of said apertures adapted to be inserted through the other of said apertures and provided with a bevelled tip to facilitate such insertion.

49. In a printing press: a base provided with an aperture; an impression member provided with an aperture positioned to aline with said aperture in said base when said member is accurately positioned on said base; and means for accurately positioning said member on said base comprising a key and a keyway formed one on said member and the other on said base, and a pin carried in one of said apertures normally retracted, adapted to be inserted through the other of said apertures, formed to be secured in inserted position, and provided with a bevelled tip to facilitate insertion.

50. In a printing press: a base provided with an aperture; an impression member provided with an aperture positioned to aline with said aperture in said base when said member is accurately positioned on said base, one of said apertures being screw-threaded; and means for accurately positioning said member on said base comprising a key and a keyway formed one on said member and the other on said base, and a screw-threaded pin carried in the other of said apertures normally retracted, adapted to be inserted through said one aperture, formed to be secured in inserted position, and provided with a bevelled tip to facilitate insertion.

51. In a printing press: impression mechanism for impressing at each operation over a limited flat section of a long web; means for supporting rolled web for unrolling; and means for feeding said web through said impression mechanism, and for removing the coil from said web, comprising a roller positioned ahead of said impression mechanism having said web passing thereover reversely curved to remove substantially the entire coil from said web, and to present said web to said impression mechanism substantially flat, and provided with sides for alining said web laterally, said sides being each adjustable laterally of said web to adjust for variations in web width and to aline said web accurately with said impression mechanism.

52. In a printing press: impression mechanism for impressing at each operation over a limited flat section of a long web; means for supporting rolled web for unrolling; and means for feeding said web through said impression mechanism, and for removing the coil from said web, comprising a roller positioned ahead of said impression mechanism having said web passing thereover reversely curved to remove substantially the entire coil from said web, and to present said web to said impression mechanism substantially flat, and provided with bevelled sides for alining said web laterally, said sides being each adjustable laterally of said web to adjust for variations in web width and to aline said web accurately with said impression mechanism.

53. In a printing press: impression mechanism for impressing at each operation over a limited flat section of a long web; means for supporting rolled web for unrolling, and to permit said web to over-run; and means for feeding said web through said impression mechanism intermittently, and for removing the coil from said web, comprising a roller positioned ahead of said impression mechanism having said web passing thereover reversely curved to remove substantially the entire coil from said web, and to present said web to said impression mechanism substantially flat, and provided with bevelled sides for alining said web laterally as the slack therein is taken up by operation of said feeding means, said sides being each adjustable to adjust for variations in web width and to aline said web accurately with said impression mechanism.

54. In a printing press: impression mechanism for impressing a web; and means for feeding said web through said impression mechanism comprising two rollers engaging one face of said web at points spaced along said web, rotary means engaging the other face of said web opposite said rollers, rotary driven members carried by said rollers, a single driving member actuating both said

driven members, and operating means for advancing said web intermittently connected to said driving member and constructed to accelerate said web gradually from rest to maximum feeding speed.

5 In testimony whereof I hereunto affix my signature.

GEORGE E. LEE.
